UNITED STATES PATENT OFFICE

2,627,739

KNITTING MECHANISM

Vincent Lombardi, South Miami, Fla.

Application April 17, 1951, Serial No. 221,430

21 Claims. (Cl. 66—135)

1

This invention relates to knitting machines and to knitting mechanism, and more particularly to knitting mechanism employed in or for a knitting machine, to manipulate a portion of a series of knitting elements, as when yarn is to be or has been fed thereto by wrap yarn-feeds, and to knitting machines embodying such mechanism.

In the use of wrap-feeds, as for example wrap fingers which move from behind a row of needles, past a portion of said row, and then behind the row at a further point theralong, and then swing back over the same course after the needles have been manipulated; wrap-feeding means which draws a yarn past a portion of a row of needles; and other yarn-feeding means which feed yarn to less than an entire circular, straight or other row of needles; the use of a normal cam means for manipulating the needles, jacks, sinkers or other knitting elements are beset with numerous difficulties and limitations. Where the wrap finger feeds yarn in the same direction that the cam ring moves, these difficulties are not so great; but even here it is ordinarily necessary to use pattern drums or other selecting means to assure the manipulation of needles in the portion of the row past which the wrap finger moves without manipulating the needles in other portions. Even with such selecting means, the efficiency of machines using wrap fingers is greatly reduced because the cam means must ordinarily rotate twice in order to manipulate the needles for the reception and knitting of yarn from one wrap finger and thereafter to manipulate the reception and knitting of yarn from an adjacent wrap finger. When, however, manipulation with needles or sinkers for the reception and/or knitting of the yarn fed on the return swing of the yarn finger, i. e. when the yarn finger moves in the direction opposite to the direction of movement of the cam ring in a stationary cylinder machine, additional major difficulties are encountered.

Since the yarn-receiving wave and the knitting wave are moving away from the point where the yarn is being paid out, undue tension of the yarn, binding of the yarn, and often breaking of the yarn tend to occur. In rotating-cylinder machines, the same general difficulties are present in all instances, and the additional major difficulties are present where yarn is paid out in a direction opposite to the knitting wave.

Various suggestions for eliminating these difficulties have been made by myself and others, and, while certain of these solve effectively certain individual ones of the problems involved and are useful in particular applications and under

2

particular conditions, there remains a great need for mechanism which will be of general application and will enable knitting to be carried out effectively and efficiently by a wide variety of types of machines in which series of wrap-feeding means are employed. It is to a provision of such mechanism that the present application is directed.

With the foregoing and other considerations in view, the present invention contemplates the provision of means including a cam, a cam carrier, and track means which guides the cam along a course past a portion of a row of knitting elements and then guides it away from this course and along a long return course back to the point of beginning. This return course may lie in a plane perpendicular to the row of knitting elements, it may extend generally parallel with the row of knitting elements, or may extend in any other suitable direction so long as the return course is in a pattern such that the cam does not affect the butts on the needles or other knitting elements during the movement of the cam over the return course. In accordance with the invention the cam carrier may form a part of or be mounted on a sprocket-driven chain, it may be guided in a groove or along a rail which may extend partially or fully about the courses followed by the cam, or track (guide) means of other type may be provided. One or more cams may be provided on the mechanism controlled by a single track means; the cams may be advancing cams, retracting cams, selective cams, or cams for other purposes; and when more than one cam is provided in connection with a single track means these cams may be of the same or different character; and any desired number of track means may be provided along or about a needle frame, a needle cylinder, a needle dial, a sinker frame, a sinker dial, or the like.

By the provision of means of such character, the direction and speed of cam-movement may be fully adapted to the wide variety of requirements found in wrap-knitting operations.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention, reference should be had to the following detailed description taken in connection with the accompanying drawings, in

55 which:

Fig. 19 is a detail view; and

Fig. 20 is a view of the portion of the track at the beginning of the operative portion of the cam movement.

In the form of construction shown in Figs. 1-8 there is illustrated a machine comprising a needle-bed 5 which, as exemplified, is stationary and in the form of a cylinder formed with vertical needle slots 6 and mounted on a base plate 7 which is stationary in the present instance. Needles 8 are slidably disposed in the slots 6. A cam ring 10 mounted on a dial plate 9 extends about the cylinder being rotatable in the present instance since the cylinder is stationary. It will be appreciated, however, that the invention is adapted for use regardless of which of the relatively-rotatable members is stationary, and that needle-beds of cylindrical and other shapes and actuating means of annular and other shapes may be mounted for relative movement in any suitable manner. The needles are formed with butts 12 and are advanced, as by a cam 14, to receive yarn from a main yarn-feed 15 followed by a knitting cam 16.

Arranged about the machine are a plurality of wrap-feeds 28 each of which is selectively operated by mechanism including driving arm 39, rocker 31a and selecting drum 32, as set forth in my Patent 2,373,126 dated April 10, 1945. Each yarn finger 28 is arranged to swing from behind the needles, past the front of the needles and behind the needles again, first in a forward direction and then in a return direction. The

number of needles encompassed by the swing of the yarn-feed will be determined by the coarseness of the gage, the type of fabric being knitted, the characters of the needles and of the yarn-feeds, and other factors. In a machine such as shown, the yarn-feeds may readily encompass forty needles in a two-and-one-half inch space. For the sake of facility of illustration, however, only twenty needles are illustrated in each such space. These spaces are indicated in the drawings by the letters A, B, C, D, etc.

In order to actuate the needles for the reception of yarn from the wrap fingers during the forward swings thereof, there is provided a form 5 of mechanism 40 comprising two advancing cams 41 one of which is shown in Fig. 6. In order to knit this yarn there is provided a similar mechanism 42 comprising two cams 43 of the character shown in Fig. 7. In order to advance the needles for reception of yarn from the yarn-feeds during their return swings, there is provided a similar mechanism 44 comprising two cams 45 of the character shown in Fig. 8. In order to knit this yarn there is provided a similar mechanism 46 comprising two cams 47 of the character shown in Fig. 4.

The mechanism 46 is shown in detail in Figs. 2, 3, 5, 5A and 5B, and a description thereof will serve to illustrate the character of the other mechanisms 40, 42, and 44.

The mechanism 46 comprises a roller chain 50 which may be constructed similarly to the usual driving chains used for parts of knitting machines. The chain runs over a track comprising a drive sprocket 51, carried on a shaft 52 which carries a pinion 53 meshing with a peripheral gear 54 carried on the base plate 7, a guide sprocket 55, in the present instance, and a tensioning sprocket 56 supported and tensioned by members 56a, 56b, and 56c. By means of this gearing the sprockets are driven in the counter-clockwise direction, thereby causing the chain to travel rearward relatively to the cylinder as the mechanism 46 travels forwardly. A frame-work comprising two parallel plates 57, 57 is carried by 35 a journal box 57a for the shaft 52 and a journal box 57b for the shaft 57c of the sprocket 55, and carries the supporting tensioning members for the sprocket 56. The journal boxes are mounted for forward movement on the dial plate 9. The plates 57, 57 may further be supported by posts 59. In order to provide a smooth course conforming with the arc of the needle-bed for the chain between the sprockets 55 and 51, there is provided a curved guide plate 58 forming a part of the track means in the present instance.

Mounted on the chain 50, by means of studs 60 and 61, are one or more (two in the present instance) travellers 62, from which a stud 64 extends inwardly. On the end of stud 64 is mounted cam 47 by means of an adjusting member 66 having a slot 66a (see Figs. 5A and 5B) thru which a clamping screw 66b extends into the cam 47. As will be seen, the slot is shaped in the present instance so that the cam 47 may be adjusted in either direction from the position shown. The unit 47—66 carries a pin 66c and is rotatably mounted on the stud 64; it is urged against a stop 67 by means of a spring 68. This assures that as the cam is carried by the chain into parallelism with the line of needles, the point of the cam will be sufficiently high, so as to be out of line with the butts (see right-hand dot-and-dash position in Fig. 4). As, however, the cam 47 comes into operative position, the unit

47-66 is turned downwardly by means of a presser strip 70, to carry the cam 47 into position for retracting the needles to knit the yarn which they have received from the wrap fingers. The presser strip 70 has an up-turned cam end 71 adapted to engage the member 66 as it is swung into parallelism with the needle-bed by the movement of the chain. For the purpose of steadyng the cam 47 the traveller 62 may have an extension 62a which slides between the upper plate 57 and a parallel guide plate 57d.

In the present instance, the yarn fingers are adapted to swing over a two-and-one-half-inch course and the gearing is designed to drive the chain rearwardly twice as fast relative to the cylinder 5 as the forward speed of the cam ring 10. Consequently, the member 70 must extend beyond the portion 71 thereof at least three and three-fourths inches, or one and one-half times the distance of a knitting zone defined by a wrap-feed swing. This two and one-half-inch swing may encompass forty needles, tho, for the sake of facility of illustration, only twenty are shown. In the present instance, the speed of movement of the cam ring about the cylinder may be 20 R. P. M. or 145 feet per minute, the diameter of the needle cylinder being twenty-eight inches.

As exemplified in Figs. 6 and 6A, the construction is similar for the mechanism 40 which raises the needles for reception of yarn from the forward swing of the wrap-feed, except that the cams 41 and the connecting members 16 face upwardly instead of downwardly, the spring 78 operates in the opposite direction from the spring 68, the stop 77 serves as a limit for downward movement, the chain 59 is operated in a clockwise rather than in a counter-clockwise direction by gearing 72, 73, and 74; and the presser strip 80 is at a lower point with its cam end 81 shaped to raise the cam 76 rather than lowering it.

As will be seen from Figs. 7 and 7A, the construction of the mechanism 42 is similar to that shown in Fig. 2, except that gearing 82, 83, and 84 is provided to drive the sprocket 55 and the chain 50 in a clockwise direction, the cams 43 and connector 86 face forward, and the pressure strip 90 has its cam end at the rear instead of at the front.

The mechanism 44, as will be seen from Figs. 8 and 8A, is similar to the mechanism 40 shown in Fig. 6, except that the cams 45 and connectors 96 face rearwardly; the chain 50 is driven in a counter-clockwise direction by a pinion 93 which rotates the sprocket 51 in a counter-clockwise direction; and the presser strip 100 has its cam end facing forward.

Mechanisms such as contemplated by the invention are adapted for use with various types of knitting elements and in various positions. There is illustrated in Figs. 9-11 an arrangement wherein a mechanism of the general character shown in Figs 1-8 is utilized for the actuation of knitting elements in a dial, in the present instance, sinkers 101 in slots 102 in a sinker bed 103. The sinkers have butts 104 for actuation by cams on a cam ring 105. The actuation of sinkers in a reverse direction is advantageous, when yarn has been fed by the return swing of a wrap-feed, in order to measure out the yarn for reception by needles which are themselves actuated by conventional means. In a number of instances, moreover, the actuation of sinkers at a speed greater than the relative speed of movement of the sinker cam ring is advantageous.

As indicated above, a wide variety of types of

track means may be employed in mechanisms such as contemplated by the invention. In the form of construction illustrated in Fig. 9, there is provided, instead of sprockets, a more conventional type of track means 109 in the form of a groove 110, having a portion 111 which is bowed to conform in contour with a sector of the row of sinker butts 104, and having also portions 112 and 113 which are adapted respectively to guide a cam carrier to and from the portion 111. A flaring portion 114 is provided to receive the cam carrier as it approaches the portion 112. Instead of using a chain to carry the cams, there is employed in the present instance, a cam carrier in the form of an arm 115, which is slidably mounted on a rotor 116 as by means of studs 117 and 117a, fitting into a slot 117b. The rotor carries a gear 118 which meshes with the stationary rack 118a on the base plate 103. The rotor is suitably journaled in a bearing 106 mounted on the dial plate 107, said bearing being arranged to also center and support the track means 109.

On one or both (both in the present instance) of the ends of the arm 115, there are pivotally mounted travellers 119 and 120, each carrying rotatable studs 121 and 122 having rollers 121a and 122a which are adapted to be received by the flaring portion 114, and to be guided by track portions 112, 111, and 113.

In Fig. 9 the course of a traveller with studs 121 and 122 thruout an entire revolution is indicated. The stud 122 trails, and, while the groove is discontinuous, there is provided in the present instance, an outer guide 123 to prevent the traveller which is away from the portion 111 from flapping. Each traveller includes a bracket 123a for mounting of a sinker cam 124 in the plane of the sinker butts 104. The cam 124 is pivotally mounted on the stud 121, but is adjustably secured to the bracket 123a by means of a bolt 125 extending thru an adjusting slot 126, whereby the extent of sinker movement may be adjusted for measurement of yarn as required for a desired length of loop. By this mounting, the cam 124 will be swung into and out of operative relation with a row of sinker butts in retracted position within individual sections about the machine, as defined by the wrap-feds.

In instances where two or more travellers are mounted on a cam carrier, there are advantages in the use of an open-ended track, but in instances where only a single traveller is employed and/or when special accuracy and certainty of control are desirable, the invention contemplates the use of a continuous track. Guide means of this character are exemplified in the construction of Figs. 12-15, in connection with a sinker dial, mounted on a needle bed, as illustrated in Figs. 9-11. In this form of construction, there is provided a track 130, having a straight portion 131, which is parallel with a row of sinker butts, a downwardly extending portion 132 leading thereto, and an upwardly extending portion 133 leading therefrom and merging with the downwardly extending portion at an apex 134. Cam carrier 135 is mounted on studs 117 and 117a extending into a slot 117b from a rotary unit 136 connected thru a set of bevel gears 137 to a pinion 139 meshing with a stationary rack 140 fastened to the base plate 141 of the machine. On one end the cam carrier 135 pivotally supports a traveller 119 formed with rotary studs 121 and 122 having rollers 121a and 122a fitting into the groove 130. As exemplified, the traveller

carries a spring pressed cam 95 operated by a presser strip 10a of the type exemplified in Fig. 2, but it will be appreciated that cams and associated mechanisms of other characters for other purposes may readily be substituted.

In the present instance the cam 95 is fastened to a bracket 140 pivotally mounted on the traveller 119. The bracket carries a roller 141, which, as soon as the cam enters the plane of the sinker butts, will engage the leading edge 70b of the presser 70a thereby swinging the cam into operative relation with the sinker butts (see Fig. 15). The remaining edge portion 70c is shaped so as to impart a circular movement to the cam concentric with the machine (see Fig. 13).

The entire mechanism is supported on the dial plate as shown for the mechanism in Fig. 3, for movement relative to the stationary rack 140. To prevent the track member 130 from revolving about its axis it is keyed at 130a to the supporting journal 136b for the rotary unit 136.

In the form of construction illustrated in Figs. 16-20 there is shown an arrangement which does not itself move relative to the bed (in this instance a needle-bed) and which includes a guide-groove parallel to the bed. In this form of arrangement a gear 150 rotatable on a stationary axis and driven from a revolving rack 151 drives a shaft 152 on which is splined a bevel gear 153 meshing with a bevel gear 154 on shaft 155 which carries a pair of guide posts 156 fitting within slot 157 in rotating arm 158. Rotatably set on one end of arm 158 is a pin 160 which carries a rotatable sleeve 161 which is guided between the sides 162 and 163 of an endless guide-groove 164 and which also carries a rotatable follower 165 freely mounted on a pin 166 carried by a U-shaped arm 167 which is freely carried on the pin 160. In this form of construction the needles, needle-cylinder, and other mechanism may be similar to that shown in Fig. 1; the needle butts being engaged by the cam 170 carried by the U-shaped arm 167 for movement from a level 171 to a level 172 in the present instance. The cam is carried on the end of a pin 173 which may be integral with pin 160.

On the pin 173 is a spring 174, the end 175 of which urges the follower 165 outwardly in the present instance. The outer wall 163 of the guide means is broken as indicated at 176 in Fig. 20 to allow the follower 165 to swing rapidly toward the needle-bed to allow the cam to come into alignment with the needle butts without delay when it approaches the butt level. Units such as exemplified may be provided at desired points about the beds for the operation of desired groups of needles as for the knitting of yarn from desired wrap-feeds, for example the yarn fed by the return swings thereof.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Reference is made to my co-pending application Serial No. 82,460, filed March 19, 1949, containing claims generic to those of the present case.

I claim:

1. In or for a circular knitting machine, track means defining a course adapted to guide a cam

carrier to carry a cam along a line at a given distance from the operative ends of a row of knitting elements and a longer return course extending away from said line and back thereto to guide the cam carrier to carry the cam back to its starting point by a unidirectional movement along said track, a cam carrier guided by said track, and a knitting-element-actuating cam on said carrier.

5 2. A mechanism as set forth in claim 1 wherein the cam carrier comprises a chain and wherein the track comprises a drive sprocket and a guide adjacent to said line.

10 3. A mechanism as set forth in claim 2 wherein said surface is arcuate and the track comprises sprockets at both ends thereof.

15 4. A mechanism as set forth in claim 1 wherein the track has a continuous extent equal to at least half the combined length of said courses, wherein the cam carrier comprises a traveller, and wherein the cam is secured to said traveller.

20 5. A mechanism as set forth in claim 1 wherein the track comprises a groove which extends in a course having a convex section to provide a shorter arcuate portion adjacent to said line.

25 6. A mechanism as set forth in claim 1 wherein there are provided two travellers movable along said track and means to join said travellers, wherein the track extends continuously along the first-mentioned course and beyond the same and has an extent equal to about half the total extent of said courses but is broken to permit one of said travellers to be free while the other is guided.

30 7. A knitting machine comprising a row of knitting elements, a cam for operating knitting elements in a portion of said row, and means to move said cam from a point at one end of said portion of said row past said portion to a point at the other end of said portion, thence away from the last-mentioned point, and back along a distant return course to the first-mentioned point.

35 8. A knitting machine as set forth in claim 7 wherein the knitting elements and the cam-moving means are mounted for relative movement along the line of said row and wherein the movement of the cam is in the line of the aforesaid movement in the opposite direction.

40 9. A knitting machine as set forth in claim 7 wherein the knitting elements and the cam-moving means are mounted for relative movement along the line of said row and wherein the movement of the cam is in the line of the aforesaid movement in the same direction.

45 10. A knitting machine as set forth in claim 7 wherein the knitting elements and the cam-moving means are mounted for relative movement on relatively stationary bases.

50 11. A knitting machine comprising a row of knitting elements, a cam for operating knitting elements in a portion of said row, and means to move said cam from a point at one end of said portion of said row past said portion to a point at the other end of said portion, thence away from the last-mentioned point, and back along a distant return course to the first-mentioned point at a speed faster than the speed of a point on the rotating bed past a point on the stationary bed.

55 12. A circular knitting machine comprising a generally circular series of knitting elements, a bed therefor, actuating means for said knitting elements, a bed for said actuating means, said beds being mounted for relative rotation, track

means defining an arcuate course adapted to guide a cam carrier to carry a cam along a course past a portion of the first-mentioned bed and thru a longer return course to guide the cam carrier to carry the cam back to its starting point by a unidirectional movement along said track, a cam carrier guided by said track means, a knitting-element cam on said carrier, and means to drive said carrier to move said cam thru said courses.

13. A circular knitting machine comprising a generally circular series of knitting elements, a bed therefor, actuating means for said knitting elements, a bed for said actuating means, said beds being mounted for relative rotation, track means defining an arcuate course adapted to guide a cam carrier to carry a cam along a course past a portion of the first-mentioned bed and thru a longer return course to guide the cam carrier to carry the cam back to its starting point by a unidirectional movement along said track, a cam carrier guided by said track means, a knitting-element cam on said carrier, and means to drive said carrier to move said cam thru said courses at a speed faster than the speed of a point on the rotating bed past a point on the stationary bed and in a direction such that its cam will have an effective action on said knitting elements in the opposite order from a cam on the second-mentioned bed.

14. A circular knitting machine comprising a generally circular series of knitting elements, a bed therefor, actuating means for said knitting elements, a bed for said actuating means, said beds being mounted for relative rotation, track means defining an arcuate course adapted to guide a cam carrier to carry a cam along a course past a portion of the first-mentioned bed and thru a longer return course to guide the cam carrier to carry the cam back to its starting point by a unidirectional movement along said track, a cam carrier guided by said track means, a knitting-element cam on said carrier, and means to drive said carrier to move said cam thru said courses at a speed faster than the speed of a point on the rotating bed past a point on the stationary bed and in a direction such that its cam will have an effective action on said knitting elements in the same order as a cam on the second-mentioned bed.

15. A knitting machine as set forth in claim 12 wherein the track is generally perpendicular to the first-mentioned bed.

16. A knitting machine as set forth in claim 12 wherein the track extends throughout its

major extent in proximity to the first-mentioned bed.

17. A knitting machine as set forth in claim 12 wherein the knitting elements are needles.

18. A knitting machine as set forth in claim 12 wherein the knitting elements are sinkers.

19. A circular knitting machine comprising a generally circular series of knitting elements, a bed therefor, actuating means for said knitting elements, a bed for said actuating means, said beds being mounted for relative rotation, track means defining an arcuate course adapted to guide a cam carrier to carry a cam along a course past a portion of the first-mentioned bed and thru a longer return course to guide the cam carrier to carry the cam back to its starting point by a unidirectional movement along said track, a cam carrier guided by said track means, a knitting-element cam on said carrier, track means forming part of said actuating mechanism and mounted on the second-mentioned bed, a cam guided by said track means through a course which extends in part along a portion of said bed and in part from one end of said portion to the other end of said portion, and driving means for said cam comprising gear means connected with each of said beds.

20. A circular knitting machine comprising a generally circular series of knitting elements, a bed therefor, actuating means for said knitting elements, a bed for said actuating means, said beds being mounted for relative rotation, a chain carried by the second-mentioned bed and having an arcuate extent lying along the first-mentioned bed, a cam carried by said chain, and gearing on said beds for driving said chain.

21. A cam arrangement for knitting machines comprising a knitting-element-actuating cam, driving means therefor, and a connection between said driving means and said cam, said connection comprising releasable means and means for adjusting the position of said cam when said releasable means is released, and said releasable means being restorable to secure said cam in its adjusted position.
